UNITED STATES PATENT OFFICE.

THEOPHILUS KALLMEYER, OF WILMINGTON, CALIFORNIA.

APPARATUS FOR LIFTING OIL IN OIL WELLS.

Application filed May 29, 1924. Serial No. 716,697.

This invention relates to an oil production apparatus for practicing the method of raising oil in oil wells.

An object of this invention is the provision of a new apparatus by which the natural gas pressure in a well may be utilized without waste of gas pressure to raise the oil, my method and apparatus providing for the utilization of said gas pressure for raising the oil in the well as the level of oil falls in the oil strata.

Another object of this invention is the provision of an apparatus for cleaning the well of obstructive matter while at the same time maintaining production and without killing the well.

A further object of this invention is the provision of a pipe adapted to be raised and lowered in a well through regular production apparatus and without shutting off the production of fluid raised from the well.

It is well known that oil as it lies in the ground is stratified, that is, there are layers of oil of different gravities in an oil stratum or a plurality of contiguous oil strata, the oil of highest gravity being lowest. It would therefore be desirable to provide a method and apparatus therefor by which the oil of different gravities may be selectively taken from the well, and it is an object of my invention to provide such method and apparatus.

With the foregoing objects in view together with such other objects and advantages as may subsequently appear, my invention consists in the method hereinafter described and claimed, and in the construction and arrangement of parts hereinafter described and claimed and illustrated in the accompanying drawings, in which:

Figure 1 is a longitudinal section of a well and apparatus therein, and an elevational view of apparatus above the well connected with the apparatus within the well.

Fig. 2 is a view similar to Fig. 1, but illustrating the downward extension of apparatus in the well adjusted for operation when the oil in the well has reached a lower level than is shown in Fig. 1, the lower level of the oil being due to the fact that the oil supply has been partly exhausted, and

Fig. 3 is a detailed elevational view, partly in section, of apparatus above the well connected with the apparatus in the well.

Referring to the drawings for a more detailed description thereof, the numeral 7 indicates a well extending into the strata 8 of oil bearing sands. The oil sands 8 are usually bounded by a superimposed layer 9 of rock or other substance which is comparatively impervious to the gas which naturally accompanies the oil.

A casing 10 extends through the well and extends above the upper end thereof. The lower end portion of the casing 10, which extends into the oil bearing sands, is provided with a plurality of apertures 11 which extend around the casing and permit oil from the surrounding sands to flow into the casing.

Within the casing 10 is positioned a vertical tube 12, the lower end of which may be in the oil bearing sands 8. The tube 12 extends upwardly through a casing head 13 which is secured to the upper end or head of the casing 10. The lower end portion of the tube 12 is provided with a plug or stopper 14 having peripheral male threads which engage female threads formed in the tube 12.

A pipe 15 is positioned within the tube 12, the lower end portion of said pipe passing through the plug 14 and extending below the oil level. A packer 17, positioned just above the stopper 14, encircles a portion of the pipe 15 and fills the space between said portion and the opposing portion of the tube 12. The pipe 15 is slidable through the packer 17 and through the stopper 14.

The upper end of the pipe 15 is connected to a usual cage 19 perforated axially and laterally. To the upper end of the cage 19 is connected a pipe 21 extending upwardly through the casing head 13 and through an assemblage of apparatus 22, known to oil men as a Christmas tree. The pipe 21 extends above the Christmas tree and is provided with lateral apertures 23 which in Fig. 1 is shown above and in Fig. 2 below the tree 22. A rod 21^a is screwed into the upper end of the pipe 21. The Christmas tree or assemblage of apparatus 22 comprises a valve 24 secured to the upper end of the tube 12.

A fitting 25 cruciform in longitudinal section is connected to the valve 24 and comprises arms 26 and 27 and a vertical branch 28, said arms and said branch being outwardly threaded. A valve 29 is connected to

the arm 26 and a nipple 30 is connected to the valve 29. A T 31 having a vertical stem 32 is connected to the nipple 30. A closed pipe 33 is secured to one end of the T to close the same. A valve 35 is connected to the arm 27 and a nipple 36 is connected to the valve 35. A T 37 having a vertical stem 38 is connected to the nipple 36 and a closed pipe 39 is connected to the outer end of the T 37 to act as a stopper or plug. A member 41 threadedly engages the upper end of the branch 28 of the fitting 25, and is provided with a stuffing box 42 in which is fitted a follower or gland 43. A nipple 45 threadedly engages the upper end of the member 41 and is connected at its upper end to a gate valve 47.

In some fields the gas pressure developed in the oil sands 8 is sufficient to lift the oil to the surface but is insufficient to lift the column of mud or water which is in the well hole and within the set well casing after the same has been cemented off and the drilling operations have been completed. It will be understood that when the drilling operations have been completed, the circulating mud or water in the well hole is disposed above the well fluid and above the oil sands 8. This mud or water or other foreign matter constitutes a fluid which is heavier than oil and in certain fields the gas pressure developed is insufficient to force the mud and circulating fluid out of the well hole. With the apparatus in position, as shown in Fig. 1, the pipe 21 connected at its lower end to pipe 15 is suspended by a solid rod 21^a by a so-called traveling block suspended from the derrick of the oil well, not shown. It should be remembered that there is the enormous weight of pipe 21, which may be from one to three thousand feet or longer. In this position of the apparatus it should be noted that the lateral openings 23 of pipe 21 are freely exposed and above the tree 22. A pump, not shown, is connected to the vertical stem 30 of the T 37 and a displacing fluid, such as oil, steam, gasoline, compressed air or the like, is pumped through a valve 35 into the tube 12 occupying the annular space between tube 12 and pipe 21. The displacing fluid should be of approximately the same density as the oil or well fluid, or in other words the displacing fluid should be lighter than the mud and circulating fluid above the well fluid. The pressure of the displacing fluid will force the circulating fluid from tube 12 through cage 19 into pipe 21, displacing the circulating fluid both in pipe 21 and in tube 12 above the cage 19 and forcing the same out through the lateral openings 23 above the tree 22.

It will be understood that a length of pipe may be inserted in pipe 21 and the same may be lowered so that the cage 19 will be at a point below the one shown in Fig. 1 in order

to remove an additional amount of the circulating fluid. In this manner the heavy mud or circulating fluid will be forcibly displaced upwardly by a lighter fluid and the weight of the column of fluid above the oil will be materially decreased. It should be borne in mind constantly that the depth of an oil well is enormous, running from two to five thousand feet in California.

The gas pressure developed in the oil sand 8 is now sufficient to allow the oil to enter through the pipe 15 and flow upwardly to the top of the well and the well is now "brought in". At this stage the traveling block, from which pipe 21 is suspended, is lowered so that the lateral apertures 23 in pipe 21 are below the tree 22, as shown in Fig. 2; though it will be understood it will be sufficient if these apertures are below the stuffing box 42. The displacing fluid pump having been stopped, the gate valve 35 is closed and the gate valve 29 is opened. The gas pressure will force the oil upwardly through tube 12 and the same will flow through the tree 22 out at the outlet 32. It is sometimes advisable in a case where there is a tremendous pressure developed and the stuffing box 42 is leaking, to put a cap 50 on top of the tree 22, as shown in Fig. 2, to confine any seepage of oil within the tree. In the position shown in Fig. 2 pipe 21 is supported above the stuffing box 42 by means of a collar or joint which rests on the stuffing box and the supporting structure.

As the level of the oil in the well falls during production, the pipe 15 is lowered in order to maintain its lower end below the oil level and thus constantly form a trap which conserves the gas pressure by preventing the escape of the gas.

If there is a tendency for the well to sand up, the pipe 15 may be raised above the level of the sand, and then lowered gradually, following the sand level down, the sand being laid through the pipe by the pressure of gas. The well may thus be kept substantially clean of sand without shutting down production and without killing the well.

In order to withdraw from the well a layer of oil having a desired specific gravity, the pipe 15 may be positioned so that its lower end is in the layer of oil having the desired gravity, which action is readily permitted by my construction.

It will thus be seen that I have provided a new method of raising oil in a well which comprises conserving the natural supply of gas and utilizing such gas to force the oil out of a well and continuously so as the oil level goes down, and I have also provided apparatus for carrying out the new method of oil production.

It will also be appreciated that the method of oil production hereinbefore described is different in part from the prior art by the

conservation of natural supply of gas done for the purpose of providing natural motive power for raising oil in a well, the methods of the prior art having allowed gas to escape and thus natural motive power to be wasted.

This invention has been described, but modifications thereof may be devised without departing from the spirit thereof, and it is to be understood that such modifications come within the scope of this invention.

What is claimed is:

1. In an oil production apparatus the combination of an outer casing perforated at the lower end, a casing head at the upper end of said casing, a stationary tube extending downwardly through said casing head, a Christmas tree mounted at the upper end of said tube, a pipe open at the bottom and closed at the top within said tube and extending below and above said tube, a packer at the lower end of said tube encircling said pipe, a second packer in said Christmas tree encircling said pipe, said pipe being slidable in said packers and provided with an opening above said lower packer and a second opening near its upper end and adapted to be disposed above said second packer when it is desired to displace the circulating fluid, or below said second packer when the well is producing, means for forcing a fluid between the tube and the pipe to displace the circulating fluid therein and force the same through said pipe and out through said second opening, and a valve controlled oil outlet in the Christmas tree communicating with said tube.
2. In an oil production apparatus the combination of an outer casing perforated at its lower end, a casing head at the upper end of said casing, a stationary tube extending downwardly through said casing head, a pipe open at the bottom and closed at the top within said tube and extending below and above said tube, a packer at the lower end of said tube encircling said pipe, a second packer above the casing head encircling said pipe, said pipe being slidable in said packers and provided with an opening above the lower packer and a second opening near its upper end and adapted to be disposed above said second packer when it is desired to displace the circulating fluid, or below said second packer when the well is producing, means for forcing a fluid between the tube and the pipe to displace the circulating fluid therein and force the same through said pipe and out through said second opening, and a valve controlled oil outlet in the Christmas tree communicating with said tube.
3. In an oil production apparatus the combination of a stationary tube, a pipe open at the bottom and closed at the top slidable disposed within said tube, means closing the lower end of the tube about said pipe, said pipe being provided with an opening above said closing means and a second opening near the upper end, means for forcing a fluid into said tube to displace the circulatory fluid therein and force the same through said pipe upwardly and out through the opening at the upper end of said tube.
4. In an oil production apparatus the combination of an outer casing perforated at the lower end, a stationary tube within said casing, a pipe within said tube and mounted for bodily slidable movement and extending above and below said tube, a packer between the lower end of said tube and said pipe, a second packer encircling the upper end of said pipe, there being an opening in the pipe above said first packer and a second opening near the upper end of said pipe adapted to be disposed above said second packer when it is desired to displace the circulating fluid, or below said second packer when the well is producing, means for forcing a fluid into said tube and pipe to displace the circulatory fluid therein, and means connected to said tube for conducting oil out of the well.

In testimony whereof I have signed my name to this specification.

THEOPHILUS KALLMEYER.
